UNITED STATES PATENT OFFICE.

GEORGE B. STEVENSON, OF UPPER SANDUSKY, OHIO.

CONNECTING-ROD.

SPECIFICATION forming part of Letters Patent No. 292,380, dated January 22, 1884.

Application filed June 11, 1883. (No model.)

To all whom it may concern:

Be it known that I, GEORGE B. STEVENSON, a citizen of the United States, residing at Upper Sandusky, in the county of Wyandot and State of Ohio, have invented certain new and useful Improvements in Connecting-Rods; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a side view. Fig. 2 is a horizontal section, and Figs. 3 and 4 are detail views.

This invention has relation to devices for adjusting the boxes of connecting-rods or pitmen; and it consists in the novel construction and arrangement of parts, as will be herein-after more fully set forth and claimed.

In the accompanying drawings, the letter A designates the end of a pitman or connecting-rod, having the loop-strap B connected thereto by bolts C, passing through perforations d of the strap.

E E' are the boxes, which are flanged at f, and are seated in the opening or slot of the 30 strap near its outer end, the outer box, E, being in contact with the end g of the strap and the inner box adjacent thereto. Between the inner box, E', and the end h of the pitman is an interval, in which the adjusting devices are seated.

K represents a wedge-form block movable in the loop-strap, and in contact with the inner box, E', by its face k. Its face l is inclined to engage the correspondingly-inclined face or bearing m of the nut N. This nut is shorter than the wedge-block K, and is designed to move in contact therewith when operated by means of an adjusting-screw, P, which engages the threaded perforation of the nut. R 40 indicates a central vertical offset of the face of the nut, whereby its middle portion is thickened to provide material for and to centralize

the threaded aperture of the nut, and the wedge-form block K is conformably recessed at t to accommodate the offset R. By this offset it will be seen that the threaded perforation is formed the full length of the nut, and the latter strengthened at a point where great strength is required. It also serves as a guide for the nut N in its vertical movement. The screw P is formed with a squared or hexagonal head, s, whereby it is turned in adjusting the wedge-nut N. It is secured in position by means of a nut, w, which engages the end of the screw which projects through the lower arm of the strap. The screw P in this manner forms a bolt through the strap, (near the boxes,) so that it is prevented from spreading. By turning the screw P to the right the wedge nut is operated to crowd the longer wedge-form slide K toward the boxes, which are thereby tightened upon the wrist. To loosen them, the adjusting-screw is turned in the opposite direction. The adjustment is effected with accuracy and ease.

70 Pitmen and connecting-rods with adjusting-screws have been provided with inclined nuts and slides for adjusting their boxes, and I therefore do not claim such, broadly.

Having described this invention, what I 75 claim, and desire to secure by Letters Patent, is—

The combination, with the strap of a pitman or connecting rod, of the adjustable nut N, having the inclined bearing and vertical 80 cylindriform offset R, strengthening the nut in its narrow portion, the wedge-form slide K, having the vertical cylindriform recess t and inclined bearing-face, and the adjusting-screw passing through the nut, wedge-form slide, and 85 strap, all adapted to operate substantially as specified.

In testimony whereof I affix my signature in presence of two witnesses.

GEORGE B. STEVENSON.
